Ges. H. Mills, Jr.

UNITED STATES PATENT OFFICE.

FRANK TUCHFARBER, OF CINCINNATI, OHIO.

ACOUSTIC STYLUS MOUNTING.

Application filed December 3, 1920. Serial No. 427,932.

To all whom it may concern:

Be it known that I, FRANK TUCHFARBER, a citizen of the United States, and a resident of Cincinnati, in the county of Hamilton and State of Ohio, have invented certain new and useful Improvements in Acoustic Stylus Mountings, of which the following is a specification.

My invention relates to sound-reproducing machines such as phonographs, gramophones, and the like, and its object is to improve the quality of the sound reproduced by such instruments.

My invention consists in the combination of parts and in the details of construction and arrangement of parts, as will herein-after be more fully described and claimed.

In the drawings:

Fig. 1 is a side elevation of a sound box of a sound-reproducing machine and its stylus provided with my invention;

Fig. 2 is a detail perspective view of a device embodying my invention;

Fig. 3 is an enlarged section on a plane corresponding to the line 3—3 of Fig. 1;

Fig. 4 is a cross-section on the same scale as Fig. 3 on a plane corresponding to the line 4—4 of Fig. 1;

Fig. 5 is a partial cross-section corresponding to Fig. 3, but showing how the invention adapts itself to a thinner stylus; and

For the purpose of illustrating the use of my invention, I have shown, in the drawing, a sound-box 1 with a diaphragm 2, to which is attached one end of the stylus lever 3 suitably mounted for correct movement by means of the mounting 4 on the lower side of the sound-box 1, and having in its lower end a holder 5 which has, opening downwardly from its lower end, a socket 6 of triangular cross-section (Fig. 4) as these sockets are usually made to adapt them for receiving either a stylus of triangular cross-

section usually made of wood or fiber, or a stylus of circular cross-section usually made of steel or other metal. Some sound-reproducing machines, however, have this socket circular in cross-section, these usually employing a metal stylus having a tip of other metal or a gem of some kind. The mechanism, as here shown, is disposed for use with records having lateral undulations, but, as will be discerned from the following description, my invention is applicable also in connection with records having vertical un-

dulations or those of other forms, and may be applied to reproducing mechanisms of varying constructions and types, the one herein shown being selected merely to illustrate the principles of the invention.

As is well known, the needles or styli are ordinarily mounted directly in the socket 6 whatever be the shape of the socket, and are held by the set-screw 7 clamping directly against the side of the needle or stylus. If the needle or stylus be of metal, either with the point of the same material or of some other material, as just mentioned, the density of the metal in the stylus is sufficient, not only to faithfully transmit the desired sound vibrations, but also to transmit certain undesirable vibrations due to imperfection in the correlation of certain parts of the mechanism, and especially to irregularity in the cooperation of the stylus with certain parts of the record undulations, so that they, with the most desirable kinds of diaphragms, which, in the majority of apparatus, are of mica, produce blasting or harsh and strident sounds at certain periods in the rendition of some selections.

To overcome these defects of the metal needle or stylus, as well as with the idea of decreasing the wear on certain kinds of records, needles or styli of various softer materials have been employed, notably various kinds of vegetable materials, such as certain woods, as well as some other materials which are less dense than metals. Some of these somewhat overcome the transmission of the undesirable sounds or noises, but they are objectionable in that they also fail to transmit many of the desired vibrations, so that they are generally incapable of reproducing a selection with the proper tone, and usually fail to reproduce sufficiently loud to be satisfactory. Moreover, while such softer materials save some wear on the records, they are themselves quickly worn out and are not dependable for very many repeated uses.

As between these two kinds of needles or styli, the metal needle or stylus, either with its point of the same or a harder material, is preferred by most users of sound-reproducing apparatus because other considerations being equal, the metal needle or stylus permits of a more faithful reproduction, and, if the ordinary steel needle or stylus, is readily renewed at each rendition, or if tipped with a sufficiently hard material and used with records intended therefor, will

continue to give faithful reproduction throughout a great number of successive renditions without noticeable deterioration, either of the needle or stylus, or the records.

5 It is the purpose of my invention to overcome the defects of the metal needle or stylus of either one of the kinds just alluded to, without materially reducing its effectiveness for faithful tone reproduction and loudness.

10 In my invention, I have introduced a material having considerable resiliency and density, and therefore capable of approximating metal in its capacity for transmitting all of the desired vibrations from the 15 record to the diaphragm, yet having such an amount of elasticity not possessed by metals that harsh, strident, blasting effects in certain parts of certain renditions are avoided.

Such a material is exemplified by a hard 20 fiber such as that used extensively in electrical insulation work. Such hard fiber, which is made from materials of vegetable origin but compressed to such an extent that the natural vegetable properties so objectionable 25 in ordinary natural fiber needles or styli are eliminated, is tough and strong similar to metal.

Other materials having the just described 30 characteristics may be substituted for the hard fiber just alluded to, and it will be understood that my invention is not limited to the use of this particular material mentioned as an example. It will be understood, however, that to be satisfactory for 35 the purpose of my invention, the material should have considerable strength and toughness and sufficient density to transmit desired sound vibrations, and have sufficient elasticity when used according to my invention 40 to prevent the appreciable passage of undesirable vibration, which latter vibrations are usually of greater amplitude than the desired ones.

In using this hard fiber or equivalent material, I do not attempt to substitute it for the material of the stylus or needle, either in the tip or the body thereof. On the contrary, my invention comprehends the use in any given sound-reproducing apparatus of 50 the kind of needle or stylus particularly adapted to the apparatus and to the records it is designed to cooperate with; as, for instance, in many kinds of apparatus, the ordinary steel needle, to be renewed at each rendition, gives the most satisfactory results, while in other apparatus needles with tips of hard material for permanent use are employed. My invention is applicable to either kind of apparatus and is adapted to eliminate such defects as the several kinds of apparatus have without any appreciable diminution of the desired tone-reproducing facilities.

Such materials as I exemplified by the 65 hard fiber do not have sufficient stiffness

to constitute a satisfactory needle or stylus body nor sufficient hardness to be at all satisfactory in the point of the stylus. At the same time, they are so dense that they are not adapted to be employed in large masses as 70 holders for the metal styli extending out from the stylus lever of the apparatus, as has been the case with certain other materials used for the same general purpose as my invention.

75 My invention differs from the various other devices for this same general purpose in the respects due to the decided difference of the kind of material employed, which is too soft and too weak to be employed as the stylus or needle itself, and too stiff and dense to be employed as a protruding part of the stylus-supporting structure; and yet

80 which is so strong and tough, as well as dense and hard, that it may form a fairly permanent part of the apparatus when properly reinforced by being held in the socket 6 itself in the form of a short tube or hollow cylinder 8, open at each end and longitudinally, with its outer walls fitting against the walls of the socket 6 and its inner walls more or less tightly fitting the outer surface of the needle or stylus 9. If so used and

85 clamped by the set-screw 7 with the right degree of tightness it virtually becomes one with the needle or stylus and the stylus lever for the faithful transmission of correct tone vibrations, and at the same time acts, due to its considerable elasticity, to absorb undesirable vibrations without transmitting them 90 from the needle or stylus 9 which it surrounds, to the stylus holder 5 and its stylus lever 3 in which it is contained.

95 Furthermore, on account of this considerable elasticity which it has, it is capable of very nicely adjusting the volume of tone transmitted, accordingly as it is clamped more or less tightly by the set-screw 7. In 100 accomplishing this adjustment, the clamping should be tight for the first trial and then gradually loosened in successive minute degrees until the desired volume of tone is ascertained by actual trial with the given record.

105 As shown herein, the needle or stylus is the ordinary kind usually made of steel or some other suitable metal; while, as before mentioned, the socket is triangular, as many of them are, for the purpose of receiving triangular styli of various soft materials. It 110 will be understood, however, that my invention is useful with the various tipped styli which have round tipped shanks and are in some apparatus fitted into around sockets. Also, some apparatus employing the ordinary metal needles have round sockets to receive the needles. In any case it will be understood that the tube or hollow cylinder 8, according to my invention, should be of the 115 approximate outer diameter to readily enter 120

but not too loosely fit the socket whether it be triangular, round or other shape, and of the right internal diameter to receive the shank of the thickest needle or stylus desired to be employed. In any instance, the socket is usually of considerably greater diameter or transverse dimension than is the thickest needle or stylus which it is to hold; so that it is permissible to have the tube or hollow cylinder or bushing 8 of ample thickness to give it the desired operating effect, as well as to make it strong enough to properly resist the disruptive tendencies of repeated clampings by the set-screw 7. With hard fiber, such as I prefer to use and with the thickness permissible in the usual socket and with the heaviest steel needle, the bushing 8 will remain serviceable for the rendition of thousands of selections if ordinary care be observed in clamping it.

In the preferred form of my invention I coat the inner wall of the cylinder 8 with a varnish or other suitable coating material which is elastic yet semi-hard and affords a surface not easily marred by the insertion of the needle. This varnish in my preferred form of my invention is applied to one surface of the fibrous material while in sheet form and after it has dried I cut the varnished fibrous material into lengths, run it through a tube forming machine and then cut the tubes or cylinders into the required lengths. These cylinders by reason of the longitudinal slit 10 can be reduced in diameter to facilitate insertion into the socket 6 and when in the socket tend to enlarge and automatically hold therein. They can also be expanded to readily receive needles of varying sizes. The material of the bushing preferably overlaps along the slit 10.

It will be understood that this bushing 8 remains in the socket 6 throughout the period of its use, being retained therein either by the friction of its outer sides with the socket walls (Fig. 6) or if it be slightly loose therein, by leaving the set-screw 7 clamped tightly enough to retain it when the needle or stylus 9 is to be removed. Used in this way, it is not only very inexpensive, but causes practically no inconvenience, because the needle or stylus is inserted into it as readily as into the socket 6, were the socket not provided with the bushing 8. With apparatus having a permanent stylus, the bushing 8 remains as permanently as the stylus itself, and the only wear or tear to which it is exposed is the slight change of adjustment which the user may desire, to reduce the volume of tone transmitted.

Also, due to its resiliency, such material as is exemplified by the hard fiber is capable of considerable yielding to adjust itself to needles or styli of somewhat less diameter than the internal diameter of the bushing, as is seen in Fig. 5. As here shown, the

wall of the tube or cylinder 8 flexes inwardly under the pressure of the clamping screw 7 and holds the somewhat thinner needle or stylus practically in the same manner as the thicker one is held in the previous examples. 70

While the device is thus capable of holding various sized needles or styli, it is to be pointed out that on account of the elimination by this device of this objectionable consequence of heavy, dense needles or styli, as hereinbefore fully pointed out, it is practicable with my improvement to invariably use the heaviest needle or stylus obtainable; or, where diminution of the volume has heretofore been resorted to by extending the needle or stylus out considerably from the holder, the use of my invention permits the needle or stylus to be set as far in as possible. In either case, it is thus possible to not merely obtain ample volume in the sound, 85 but to render many sounds faithfully, which, with the thinner needles or styli or with the extended adjustments, were almost wholly lost. Heavy metal needles or styli or short extensions of them from the holder have been discouraged in apparatus as heretofore provided, because with these provisions, the blasting in certain parts of most renditions is extremely disagreeable; with the result that users sacrifice many of the 90 fine and pleasing details of selections, as they had to in using the thinner or more extended styli, in order to avoid the positively disagreeable noises which must attend the use of a heavy stylus or one adjusted to render 95 all of the details of the selection. 100

It will therefore be understood that while the device is adjustable to various thicknesses of styli, it generally renders the use of thinner needles or styli, unnecessary, because it practically eliminates all of the objectionable consequences which dictated the use of such thinner styli.

So far as the thinner needles or styli were useful where reduced volume was desired, 110 as in small rooms, this reduction of volume is practically attained with my invention by very slightly loosening the clamping upon the bushing or tube 8 as hereinbefore described. This reduces the volume satisfactorily in such cases, and, at the same time, does not lose the fine and pleasing details of the rendition as is often the case where a thinner needle or stylus is substituted, or where the needle or stylus is 115 extended far from the holder in order to reduce the volume of sound transmitted. 120

The heavy needle or stylus, not extended so far from the holder as to lose important parts of the rendition due to its own flexibility, is the best means for transmitting to the diaphragm 2 all of the correct tone vibrations, whether this needle or stylus be the ordinary metal kind or one tipped with a hard material. My improved bushing or 125 130

mounting 8 of hard fiber or equivalent material is adapted to permit such a needle or stylus, so adjusted, to function practically to its maximum extent in the respects just noted, and at the same time to prevent such needle or stylus transmitting undesirable noises.

What I claim is:

1. A stylus mounting independent of the stylus and the holder therefor, composed of a stylus bushing adapted to substantially surround styli of various sizes, said bushing formed of a fibrous material and provided with a longitudinal opening extending throughout the length of the wall thereof so as to permit increase or decrease in the size of the bushing.
2. A stylus mounting consisting of a cy-

lindrical elastic bushing independent of but adapted to substantially surround acoustic 20 styli of various sizes, said bushing having a longitudinal opening in the wall thereof, so as to permit the cylindrical size of said bushing to be changed to accommodate styli of various sizes.

3. A cylindrical stylus mounting provided with an opening in the wall thereof whereby the cylindrical size of said mounting may be changed to accommodate styli of various sizes, said bushing formed of a resilient 30 material coated on the inner face with an elastic varnish adapted to maintain the mounting at its normal cylindrical size, while permitting same to be readily changed to accommodate styli of various sizes.

FRANK TUCHFARBER.
